KITCHEN UTILITY DEVICE

Alfred C. Gilbert, North Haven, and Shirley P. Morse, East Haven, Conn., assignors to The A. C. Gilbert Company, New Haven, Conn.

Application December 30, 1932, Serial No. 649,582

6 Claims. (Cl. 259—131)

This invention relates to kitchen utility devices of the type in which an electric motor supplies power for the mixing or beating of materials, the extraction of fruit juices, etc.

5 One of the objects of our invention is to provide a device of this kind which is simple, sturdy and inexpensive.

Another object is to furnish a device which can be operated very conveniently by the housewife.

10 To these and other ends the invention consists in the novel features and combinations of parts to be hereinafter described and finally pointed out in the claims.

15 In the accompanying drawings:

Fig. 1 is a front elevation of a device embodying our improvements, the juice-collecting bowl and fruit reamer being omitted;

Fig. 2 is a side elevation of the structure shown in Fig. 1;

Fig. 3 is a top plan view of the same;

Fig. 4 is a side elevation of the upper part of the structure showing the juice-collecting bowl and fruit reamer in position;

Fig. 5 is an enlarged section on line 5—5 of Fig. 2;

Fig. 6 is an enlarged section on line 6—6 of Fig. 2;

Fig. 7 is a section on line 7—7 of Fig. 5;

Fig. 8 is a front view of the gearing shown in Fig. 6;

Fig. 9 is an enlarged section on line 9—9 of Fig. 1;

Fig. 10 is a section on line 10—10 of Fig. 6;

Fig. 11 is an enlarged vertical section through the juice-receiving bowl and fruit reamer showing the mounting of the reamer shaft;

Fig. 12 is a section on line 12—12 of Fig. 11;

Fig. 13 is a detail perspective view of the bowl-supporting bracket;

Fig. 14 is a sectional view of the gear case illustrating a somewhat modified form of gearing for driving the agitator shafts;

Fig. 15 is a detail view taken at right angles to Fig. 14; and

Fig. 16 and 17 are views showing still further modifications of the gearing.

In its general features our device as particularly illustrated herein comprises a base adapted to support bowls and receptacles of various kinds; a pedestal rising from the base; a bracket pivoted to the pedestal in a position to overhang the base; an electric motor supported on top of the bracket; a gear case and gearing supported from one end of the motor; agitator shafts depending from the gear case and adapted to project down into a receptacle supported on the base to stir the contents of the receptacle; an extractor shaft adapted to be mounted to project upwardly from the gear case to drive a reamer located in a juice-

collecting and delivering bowl; and a bracket supported on the motor at the upper part thereof and by means of which the juice-collecting bowl is held in position, the bowl being removable from the bracket and the reamer shaft being removable from its operative position in which it extends upward from the gear casing.

In the example selected for illustration, the base is indicated generally at A, the pedestal at B, the motor bracket at C, the motor at D, the gear case containing gearing driven from the motor shaft at E, the depending agitators at F, the fruit reamer at G, the juice-collecting bowl at H, and the bracket supporting the juice-collecting bowl at I.

The base A may be of any usual structure and need not be particularly described. The pedestal B rises from the rear end of the base A, and the motor-supporting bracket C is mounted to swing up and down relatively to the pedestal B and is also capable of turning movement relatively thereto so that the agitators F can be swung laterally relatively to the base to bring them into the position desired for the operation to be performed or to bring the juice-collecting bowl H, if desired, to one side or the other of the base. In the particular form shown the pedestal B is of round cross-section and hollow and at its upper end provides a swivel mounting for a platform 20. At its upper end the pedestal B has a cylindrical opening or socket 21 in which is received a downwardly projecting substantially cylindrical hub or trunnion 22 preferably formed integrally with the platform 20. The hub or trunnion 22 is provided with an annular circumferential groove 23, and a set screw 24 projecting through the wall of the hollow pedestal near its mouth is adapted to engage with a certain amount of friction the bottom of the groove 23 so that the platform 20 may be caused to turn in its socket with the proper amount of friction to hold it in position after it has been swung to the desired position angularly with respect to the pedestal and base. Projecting upwardly from the platform 20 and preferably integral therewith is a fork having arms 25 between which the motor bracket C is pivoted by means of a pivot pin 26. This mounting provides for the swinging of the motor bracket in a vertical plane so that the agitators F can be moved upward to clear a receptacle mounted on the base A. After the dripping of material from the agitators F into the receptacle has ceased the bowl or other receptacle may be removed from the base in a lateral direction. The bracket C has a downward projection 27 in front of the pivot pin 26 adapted to engage the upper surface of the platform member 20 so that normally the bracket will be supported in a substantially horizontal position. The platform member 20 acts

s a base member for the fork in which the motor bracket is pivoted.

Somewhat in front of the pivot pin 28 the racket C is provided with an upwardly extending lug 28 that extends adjacent a rearwardly facing surface 29 on motor D, as shown particularly in Fig. 9, and the motor D is secured by appropriate means to the lug 28. In the embodiment illustrated, bolts 30 extend through the motor casing from end to end and nuts 31 on said bolts are disposed between lug 28 and the rear end portion of the motor, and nuts 32 are placed on the rear ends of the bolts and engage the rear face of the lug 28. The motor is also secured to the racket by end extensions 33 on an intermediate and 34 of the motor structure projecting down alongside the bracket C at its opposite faces and secured thereto by a transverse bolt 35. In this manner the motor is firmly and rigidly applied to the bracket so as to be movable therewith.

The gear case E previously referred to is applied to the casing of the motor at the front end of the casing. Preferably the front end of the motor casing is flat. The rear wall 36 of case E conforms to the front wall of the motor casing and is removably secured thereto by means of screws 37. The gear case E is relatively shallow and extends substantially diametrically with reference to the motor. Attached to the motor shaft and forming an extension thereon is a screw or worm 38 extending transversely of case E and substantially at the middle thereof and engaging a gear 39 located in case E at one end thereof. Gear 39 is of substantial depth or thickness and in the region above worm 38 it engages a shallow gear 40 arranged in the opposite end portion of the case and overlying the gear 38. The gear 39 has a long hub 41 projecting down into a bearing sleeve 42 formed integrally with the gear case. On top of bearing sleeve 42 is a thrust bearing 43 interposed between said sleeve and the lower face of gear 39. Gear 40 has a long hub member 44 projecting down into a bearing member 45 formed integrally with the lower wall of the gear case. Bearing sleeve 45 is extended within the gear case to such a degree as to engage the lower surface of the narrow gear 40. In the particular case shown the gears 39, 40 are helical gears.

Hub member 41 of the wide gear has an extension 46 projecting upwardly out of the cover 47 of the gear case and at its upper end this extension 46 has a square socket 48. Beneath the socket 48 a spring 49 embraces the hub extension 46 and acts on a ball 50 projecting into the bore of the gear hub for the purpose of yieldingly locking in place the spindle 51 of one of the agitators F. The spindle 51 has a beater 52 applied to the lower end portion thereof, said beater having blades or agitating elements of any desired form. Near its upper end the spindle 51 has a squared portion 53 adapted to engage a square socket 54 formed in the gear hub 41 at the lower end thereof. Above the square portion 53 spindle 51 is provided with a reduced cylindrical portion 55 projecting up into the gear hub and having adjacent its upper extremity an annular groove 56 adapted to be engaged by the ball 50 previously mentioned. Thus, as the agitator spindle 51 is moved up into the socket in gear 39, portion 53 non-rotatably engages a portion of the socket, and the spring pressed ball 50 engaging the groove 56 holds the agitator spindle against dislocation relatively to the gear, nevertheless permitting the removal of the spindle from the gear when that is desired.

Agitator spindle 57 is mounted in hub 44 of gear 40 in substantially the same manner as spindle 51 is mounted in hub 41, and therefore a detailed description of this latter mounting will be unnecessary.

A thrust bearing to take up end thrust on the worm 38 is preferably provided in association with the outer end of the worm. In the particular case shown, the outer end of the worm has a concave surface receiving an anti-friction ball 58, and the opposite face of the ball is engaged by a screw 59 having a concave face. The screw 59 has threads engaging interior threads in a hole passing through the front wall of gear case E, and located on the screw 59 at the exterior of the gear case wall is a nut 60 by means of which screw 59 may be locked in the position to which it is adjusted. In this manner a simple and yet efficient form of anti-friction thrust bearing for the worm 38 is provided.

The square socket 48 previously mentioned, which is located in the upper end portion of the hub of gear 39, serves to receive the lower end of a juice extractor shaft 61, as shown more particularly in Fig. 11. Shaft 61 carries at its upper end a reamer 62 for extracting fruit juices, and when agitator spindle 51 has been removed from gear 39, reamer shaft 61 may be engaged with said gear to be driven thereby. Near the lower extremity of shaft 61 the same is provided with a square portion 63 adapted to fit square socket 48, and below square portion 63 the reamer shaft is reduced in diameter and shaped cylindrically so as to form a member extending into and closely fitting the bore in gear 39. The lower cylindrical portion of the shaft is shown at 64, and it will be noted that in the operative position portion 64 preferably extends downwardly past the body or web 39 of the gear 39, as shown in Fig. 11.

The reamer 62 is disposed within the juice-collecting bowl H previously mentioned. This bowl H is removably mounted on the motor, and for this purpose the bowl-supporting bracket I previously mentioned is provided. The bracket I is preferably shaped as shown in Fig. 13, being made out of sheet metal and having a body 65 provided with a rectangular opening 66 adapted when the bowl is set down upon the bracket to be engaged by a rectangular projection 67 on the lower face of the bowl surrounding the opening 66 in the bottom of the bowl through which the reamer 61 extends upwardly. The bracket has an integral foot 69 depending from its front margin engaging the upper face of the gear case E, and at its rear edge the body of the bracket is turned downward to provide a flange 70 having notches 71, 72 adapted to engage bolts 73, 74 on the motor. These bolts are usually the bolts by which the parts of the motor are held together at the upper part of the motor, and nuts 75, 76 on the front ends of these bolts are adapted to engage the front face of flange 70 in order to secure bracket I firmly to the motor casing. The body of the bracket provided with the opening 66 having non-rotatable engagement with the bowl is preferably disposed in a horizontal plane and spaced upwardly from the top of the gear case E. The bowl H is preferably provided with a discharge spout 77 in the bottom thereof by means of which juice may be discharged from the bowl into a suitable receptacle.

In the use of our device bowls of different sizes, and other receptacles, can be positioned on the base A for co-operation with one or both of the agitators F. Either agitator may be removed

from its socket without interfering with the operation of the other agitator. In mixing beverages, for example, it will be advisable to use only one of the agitators, and in such case the agitator 5 will extend downwardly into a glass or the like containing the beverage, said glass being supported on the base. When it is desired to extract the juice from oranges, the right hand agitator shown in Fig. 1 is removed, the bowl H is placed 10 in position on the bracket I, and the reamer G is placed in operative position, its shaft being passed down through the opening in the bottom of the bowl and through the opening in the bracket I to engage one of the gears in an operative manner, as has been hereinbefore described. 15

In the form of our invention shown in Figs. 14 and 15, the intermeshing gears which drive the agitator spindles are spur gears rather than helical gears. In this case the worm 38^a driven by 20 the motor shaft has its tooth form somewhat altered so that it will drive a wide spur gear 39^a which in turn drives a narrow spur gear 40^a.

In the form shown in Fig. 16, two spur gears 25 of equal depth are employed, said gears intermeshing. In this case the worm 38^b driven from the motor shaft meshes with a worm gear 38^c having a hub 38^d to which a narrow spur gear 39^b is fixed, said gear 39^b meshing with a similar narrow spur gear 40^b.

In the form shown in Fig. 17, the motor shaft and the two gears driving the agitator spindles are all located in the same plane. In this particular case the motor shaft carries a worm or screw 38^e engaging a narrow spur gear 39^e associated with one of the agitator spindles, and a narrow spur gear 40^e is located in the same plane as gear 39^e and driven thereby. As in previous cases the gear element on or associated with the motor shaft drives a gear element associated 40 with one agitator spindle and the other agitator spindle gear is driven from the gear associated with the first spindle by direct engagement or mesh therewith.

The appliance is a very useful one for the 45 housewife and yet it is simple in construction and can be manufactured at relatively low cost.

Various changes can be made in the details of the structure herein described without departing from the principles of our invention. We have 50 not attempted to describe the various modifications which fall within the scope of our invention as defined in the claims.

What we claim is:

1. In a device such as described, the combination of a base, a pedestal rising therefrom, a bracket pivoted to the upper end of the pedestal to swing in a vertical plane, a lug rising from the bracket and detachably secured to the rear end portion of the motor, a band encircling the motor 55 structure and forming a part of the motor casing and having portions secured to the bracket at the sides thereof, a gear case secured to the motor and containing gearing driven from the motor shaft, and an agitator spindle driven from said gearing and adapted to stir the contents of a receptacle supported on said base.

2. In a device such as described, the combination of a base, a pedestal rising therefrom, a bracket pivoted to the pedestal to swing in a 60 vertical plane, a motor secured to the bracket, a gear case secured to the motor at the overhanging end of the latter and containing gearing driven from the motor shaft, an agitator depending from said gear case and driven from 65 said gearing, a bracket secured to the front end

portion of the motor and having a substantially horizontal apertured portion, a bowl supported on said bracket and having a projecting part on the bottom thereof non-rotatably engaged with the apertured portion of the bracket, said bowl having a spout leading therefrom, and a reamer in said bowl having a shaft extending down into the gear case and operatively engaging the gearing in said case. 5

3. In a device such as described, the combination of a pedestal, a bracket pivoted thereto, a motor mounted on the bracket and having its shaft horizontally arranged, a gear case located at the overhanging end of the motor and containing gearing driven from the motor shaft, a 10 bracket having a horizontally disposed portion spaced vertically above the gear case, means securing said bracket to the motor, means supporting said bracket from the gear case, a horizontally disposed juice-receiving bowl having its 15 bottom supported on said bracket, and a reamer in said bowl driven from said gearing, said bracket having an aperture therein with which the bowl bottom is non-rotatably engaged. 20

4. In a household mixer, the combination of a 25 motor having a horizontal shaft, a worm on said shaft, a gear located in a horizontal plane at one side of the worm, a second gear also located in a horizontal plane with its axis spaced from that of said first gear, and said first gear having 30 integrally related portions provided with teeth meshing respectively with said worm and second gear, said second gear being relatively narrow with respect to the width of said first gear and lying in a plane vertically offset from that of the worm shaft, a casing surrounding said worm and gears, and agitator devices depending from the respective gears and driven thereby. 35

5. In a household mixer, the combination of a 40 motor having a horizontal shaft, a worm on said shaft, a gear located in a horizontal plane at one side of said worm, said gear being relatively wide with respect to the worm diameter, a relatively narrow gear also in a horizontal plane having its axis spaced from, and parallel to, that 45 of the first gear, said first-named gear having integrally related parts provided with teeth, said teeth meshing with said worm adjacent one part of the gear and meshing with the teeth of said second gear at another part of said first gear vertically offset from said first part, a casing surrounding said worm and gears, and agitator devices depending from the respective gears and driven thereby, and said worm being disposed 50 between the axes of said gears. 55

6. In a device such as described, the combination of a motor, a horizontally disposed worm driven by said motor, a gear case secured to the motor casing in which said worm is disposed, a gear horizontally disposed in said gear case and being of greater depth than said worm so that the body of the gear extends beyond the zone of the worm, a second and shallower gear having its axis parallel to the first and spaced therefrom, and said first gear having integrally related portions provided with teeth, the teeth at one portion of said gear being engaged by said worm, and the teeth at another portion of said gear vertically offset from the first portion being engaged by the teeth of said second gear, and agitator elements depending from, and driven by, 65 the respective gears. 70

ALFRED C. GILBERT.
